UNITED STATES PATENT OFFICE.

VICTOR LE BEAU, OF NEW ORLEANS, LOUISIANA.

ELECTRIC-LIGHT FIXTURE.

Application filed January 2, 1924. Serial No. 683,986.

To all whom it may concern:

Be it known that I, VICTOR LE BEAU, a citizen of the United States, and a resident of New Orleans, in the parish of Orleans and State of Louisiana, have invented certain new and useful Improvements in Electric-Light Fixtures, of which the following is a specification.

This invention relates to an electric fixture 10 for commercial purposes and has for its object the provision of a device for producing a soft, subdued and shadowless light and at the same time sufficiently brilliant and concentrated for illuminating the entire interior of a room regardless of the color of the ceiling, walls or floor and evenly distributing the light throughout the same.

A further object of the invention is the provision of a simple and inexpensive lighting fixture in which a pair of electric lamps are maintained in axial alinement but in opposed relation, each lamp being enclosed within a translucent globe with the globes likewise being in opposed relation and separated from each other by a reflector whereby the light rays are harnessed within the enclosures and reflected on the surface of the globe by means of the reflector, the intensity of the rays being increased so that more light 30 is produced and a less waste of the rays.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the 40 invention as expressed in the appended claims.

In the drawings:

Figure 1 shows a view in elevation of a light constructed in accordance with my invention.

Figure 2 is a vertical section of the same.

Figure 3 is a side view of substantially the same form of light shown in Figures 1 and 2 but held in a horizontal position.

Figure 4 is a sectional view in detail showing the disposition of the electric wires through the supporting rods of the light.

Figure 5 is a vertical section of a modified form of lamp shown in Figure 1.

Figure 6 is a side view of the form of lamp shown in Figure 5.

Figure 7 is a further modified form of the lamp.

Figure 8 is a side view of a further modification showing the simplest form of the invention.

Referring more particularly to the drawings, 1 designates a metal disc having its opposite sides treated to form a pair of opposed reflectors. A ring 2 has an annular groove 3 formed by indenting the metal of the ring which is adapted to receive the periphery of the metal disc 1 for supporting said disc centrally of the ring, thereby providing opposed flanges 4 and 5 upon opposite sides of the disc to receive the inner open ends 6 of a pair of opposed globes 7 and 8. Set screws 2^a threaded into perforations in the ring 2 are adapted to engage grooves in the globes 7 and 8 for securing the globes in position on the ring.

The disc 1 has secured to its opposite faces at the central portion, a pair of opposed sockets 9 and 10. These sockets are of the usual form and have a porcelain outer casing 80 and an inner corrugated or threaded metal sleeve adapted to receive the threaded plug portion of the lamp 11.

A U-shaped tubular member having legs 12 and 13 has its outer free ends threaded and passed through perforations diametrically disposed in the reflector 1. Nuts 14 located upon opposite sides of the disc readily lock the ends of the U-shaped member to said disc. Extending upwardly and in substantially the same plane with the legs 12 and 13 is a tubular member 15 having an eye 16 secured to the upper threaded end of the tubular member 15 by means of a threaded sleeve 15^a. The eye 16 provides means for suspending the electric fixture from a fixed part of a room.

The tubular legs 12 and 13 and the pipe 15 provide a conduit for receiving and sealing the electric wires 17 and 18 which are connected with the house current at one end and with the sockets 9. It will be seen that the globe 7 is provided with a perforation at its upper end through which is inserted the tubular member 15, the globe embracing the legs 12 and 13 of the supporting bracket.

If it be desired to support the fixtures in a horizontal position instead of the vertical position shown in Figure 1, the chain 19 is connected to the perforated lug 20 secured to and formed integrally with the ring 2 and at right angles to the axis of said ring; the

wires 17 and 18 being passed through a perforation in the ring adjacent the lug 20. When the fixture is supported in a horizontal position the bracket carrying legs 12 and 13 are omitted.

Referring to the modified form shown in Figures 5 and 6, a ring 21 is shown having a groove 22 in which is adapted to be seated opposite ends of an insulating strip 23, the ends of the strip being secured in any approved manner as by a U-shaped member 24 which is riveted to the strip with the metallic U-shaped member being soldered or welded to the metal ring 21. A pair of sockets 25 are secured in axial alinement to the strip 23 by means of bolts 26, the bottoms of the sockets being adjacent each other and seated upon the strip. The sockets are so connected that electric wire 27 is connected with one binding post while a wire 28 is connected with an opposite binding post on the other socket, the central contact members of the sockets being connected.

25 The wire 27 is connected to a binding post 29 mounted upon a conducting member 30 which is secured to one face of the insulating strip 23. An electric wire 31 is connected with said strip through a binding post 32 and passes through a perforation in a cap 33 mounted upon the end of a cylindrical insulating member 34. Wire 28 is similarly connected to a conducting member 35 mounted upon the insulating bar 23, the conducting member 35 being connected to an electric wire 36 which is likewise carried through the perforation in the cap 33 and concealed within the insulating sleeve 34.

A chain 37 connected with a perforation 40 in the outer projecting end of the insulating member 23 is carried through the cap 33 and adapted to be connected to a fixed part of the building for supporting the light. A pair of globes 38 and 39 are maintained 45 within the ring 21 by the usual set screws as is well known, the globes enclosing the lamps 40 which are mounted in the sockets 25.

A further modified form is shown in 50 Figure 7 which is similar to the form shown in Figures 1 to 3 inclusive and includes the ring 2^a for securing a pair of globes in position the double faced reflector 1^a, a pair of sockets 41 connected upon opposite sides 55 of the reflector and in axial alinement. Insulating binding posts 42 are secured at the upper end of the bracket and to the ring 2 and are connected by means of wires 43 and 44 to the sockets 41 upon opposite sides 60 of the reflector 1. The binding posts are connected by means of wires 45 and 46 to the usual house current. The reflector 1^a is provided with a lug 47 projecting through a slot in the ring 2^a and has a perforation 65 which is adapted to receive the link of a

chain 48 whereby the bracket is supported in the horizontal position from the wall of the room.

A still further modified form of fixture is shown in Figure 8 in which a metal disc 49 has its opposite faces coated with porcelain to act as a reflector. Sockets 51 are secured in axial alinement to the central portion of the disc and for receiving the usual lamps 52. Wires 53 extend from the sockets 75 and are connected with the house current in the usual manner. A chain 54 is connected to a perforation in the upper end of the disc 49 for the purpose of supporting the disc from the ceiling of the room. 80

It will be noted that the axial alinement of the lamps having the reflectors for projecting the light rays in opposite directions provides a lamp which will give not only a light similar to the indirect light but the 85 intensity of the light will be greater so that all portions of a room will be properly and thoroughly lighted by said fixture.

What I claim is:

1. An electric fixture comprising a plate 90 having its opposite faces provided with reflectors, lamp sockets secured to the opposite faces and in axial alinement, means for suspending the plate from a fixed part of a building, and globes enclosing the sockets 95 and the opposite faces of the plate, said reflectors being adapted to generally reflect the light rays parallel to the axis of the lamps.

2. An electric fixture comprising a plate 100 having its opposite faces provided with reflectors, lamp sockets secured to the opposite faces and in axial alinement, means for suspending the plate from a fixed part of a building, said plate being provided with oppositely projecting flanges, and globes having their inner ends embraced by the flanges and secured thereto, said globes being axially alined with the sockets, said reflectors being adapted to generally reflect 110 the light rays parallel to the axis of the lamps.

3. An electric fixture comprising a plate having its opposite faces provided with reflecting surfaces, lamp sockets rigidly secured centrally of and to the opposite faces of the plate, the sockets being located in axial alinement, electric wires connected with the sockets, and globes enclosing the sockets and secured to the opposite faces of the plate and in axial alinement with the sockets, said reflectors being adapted to generally reflect the light rays parallel to the axis of the lamps. 115 120

4. An electric fixture comprising a plate 125 having its opposite faces provided with reflecting surfaces, lamp sockets secured in axial alinement to the opposite faces of the plate, a ring secured to the periphery of the plate and providing flanges projecting op- 130

positely from the faces of the plate, said plate having a perforated lip projecting through and beyond the ring and providing means for suspending the fixture from a fixed part of a building, and binding posts connected with the ring, insulated therefrom and connected with the sockets.

5. An electric fixture comprising a plate

having its opposite faces provided with reflecting surfaces, a source of light at each 10 face of the plate, and means for suspending the plate vertically from a fixed part of a building, and translucent globes secured to the opposite faces of the plate.

VICTOR LE BEAU.
